CARD SORTER

George H. Kress, Johnson City, Charles J. Jaworski,
Poughkeepsie, and James J. La Due, Hopewell Junction,
N. Y., assignors to International Business Machines
Corporation, New York, N. Y., a corporation of New York

Application April 25, 1955, Serial No. 35,655

Term of patent 14 years

(Cl. D64—11)

FIG. 1

Fig. 1 is a perspective view of a card sorter showing our new design looking at it obliquely from the front side.

Fig. 2 is a perspective view of the sorter of Fig. 1, as viewed obliquely from the rear side.

The essential features of our design reside in the portions shown in solid lines on the drawings.

We claim:

The ornamental design for a card sorter, as shown and described.
